FRED W. FARRINGTON AND SENECA BARTON BURCHARD, OF MINNEAPOLIS,
MINNESOTA.

PLASTER-LATH.

No. 857,611.

Specification of Letters Patent.

Patented June 25, 1907.

Application filed February 12, 1906. Serial No. 300,726.

To all whom it may concern:

Be it known that we, FRED W. FARRINGTON and SENECA BARTON BURCHARD, of Minneapolis, Hennepin county, Minnesota, have 5 invented certain new and useful Improvements in Plaster-Lath, of which the following is a specification.

The object of our invention is to provide a lath which will be inexpensive to manufacture, 10 easily handled and placed on the wall, and will take the place of the expensive metal lath usually used.

A further object is to provide a lath which will be lighter in proportion to its area than a 15 metal lath, and consequently will not require a backing or frame of such a substantial nature as is generally used or required for a metal lath.

The invention consists, generally, in providing a lath or board composed of plaster of 20 paris containing, preferably, a suitable percentage of fibrous material and reinforcing wires included by the thickness of the lath, and bracing and strengthening the same.

25 In the accompanying drawing forming part of this specification, Figure 1 is a sectional view of a plaster lath embodying our invention. Fig. 2 is a plan view showing a modified means for arranging the reinforcing wire therein. Figs. 3, 4, 5 and 6 are similar views illustrating other modifications in the 30 arrangement of the reinforcing wires. Fig. 7 is a perspective view of the lath, and Fig. 8 is a transverse sectional view showing the position of the wires in the lath.

35 In the drawing, 2 represents a lath or board generally made about four inches in width and from three to four feet in length, and composed of a mixture of plaster of paris 40 and a fibrous material, usually ground straw or chaff or comminuted wood, mixed in suitable proportions, and pressed together in a mold. The fibrous material being mingled with the plaster of paris will bind the particles together and act as a bond uniting the plaster in one homogeneous sheet, which will be tenacious and possess flexibility to a considerable degree, sufficient at least to allow the lath to be nailed on a surface and slightly 45 bent, if necessary, without breaking. The proportion of fibrous material in the lath may be varied according to the degree of tenacity required and the size of the lath and the desired maximum of cost. The larger the per-

centage of fibrous material for a lath of given 55 dimensions the lower will be the cost of production.

For the purpose of reinforcing the lath we embed a wire 3 therein during the molding operation, extending it from end to end and 60 crosswise thereof in a direction parallel with the edges, as shown in Fig. 1. This wire is of suitable gage, and while not adding materially to the weight of the lath will greatly strengthen it and permit it to be handled and 65 nailed on the wall without danger of breakage. The wire at the ends of the lath is preferably located at a point where the nails are usually driven through, and the nail shank passing through the lath, either inside or outside 70 of the wire and contacting therewith, will, when the head is driven into the surface of the lath, lock is securely on the wall. If the nails are driven through between the transverse sections of the wire and contact 75 therewith, the lath will be securely held against bending or buckling between the nail points.

In Figs. 2, 3, 4 and 5 we have shown a lath 80 wherein the wire is laid in transverse ways representing in Fig. 2 substantially the form of the letter Z and a figure 8 in the next illustration, and looped designs in Figs. 4 and 5.

In Fig. 6, also shown in section in Fig. 8, the wires are preferably in the form of rods 85 laid or embedded in the lath independently of one another and extending from end to end and crosswise thereof at intervals. We have indicated the longitudinal wires in Fig. 8 by numeral 4, and the position of the trans- 90 verse wires is indicated by dotted lines in Fig. 6.

As shown in all the figures, we prefer to provide beveled longitudinal edges 5 for the laths which, when they are secured on the 95 wall, will form grooves between the abutting laths to permit the entrance of the plaster and provide means for binding it more securely on the lath.

I claim as my invention:

A plaster lath consisting of a flat comparatively thin sheet rectangular in form and composed of a mixture of plaster of paris and a fibrous material molded together and a reinforcing wire included by the thickness of 100 said lath and extending from end to end and from side to side of the middle line thereof, and having its end or transverse portions 105

near the points where nails are usually driven through the lath, whereby the shanks of the nails will contact with said transverse portions and tension the longitudinal sections of the wire and lock the lath securely on the wall and prevent it from bending and buckling.

In witness whereof, we have hereunto set our hands this 5th day of February 1906.

FRED W. FARRINGTON.
SENECA BARTON BURCHARD.
